UNITED STATES PATENT OFFICE.

ANDREW P. MURRAY, OF JACKSON, MICHIGAN.

BOTTLE WASHER.

Application filed November 14, 1922. Serial No. 600,820.

This invention relates to cleansing the exterior of containers.

This invention has utility when incorporated in a bottle washer for operation in conjunction with sterilizers, of the general type shown in U. S. Patent 1,463,763, C. H. Loew, et al., July 31, 1923.

Referring to the drawings:—

Fig. 1 is an end elevation of an embodiment of the invention in connection with a sterilizer, parts being broken away;

Fig. 2 is a fragmentary section on the line II—II Fig. 1; and

Fig. 3 is a plan view of the structure of Fig. 2.

Bottle washer and sterilizing apparatus is provided with a main frame 1. Carried by this main frame 1, is motor 2 having shaft 3, connected through speed reduction gearing 4 for driving endless conveyer 5, having parallel series of bottle seats 6. The discharge end of this sterilizer or bottle interior washer and cleanser has guide 7 for retaining the bottles 8 in the seats when coming over the bend. As the bottles pass from this guide 7, transfer pockets 9 operable in synchronism with the conveyer 5, deposit the transverse series of bottles 8 on table 10. These cleaned bottles 8 deposited on the table 10, may be shifted by pusher 11 operable from the main motor 2 through the conveyor operating mechanism, over to conveyer 12 for delivery to a bottle filling machine for filling the bottles with milk.

In delivering bottles into the pockets 6 of this bottle interior washer and sterilizer, there is provided herein a bottle exterior washer. A frame 13 is disposed to carry a support or platform 14, over which is disposed, in parallel, a plurality of rotary brushes 15 operated in a common direction so that each of the intermediate brushes tends to rotate a bottle therebetween as carried by the support 14.

From the motor 2 is shown transmission connections for rotating shaft 16, having bevel gear connections to shafts 17 mounted in frame 18. Each of these shafts 17, carries a brush 15. Above this frame 18 is a spray means 19 providing a flow of wash water which may be adjusted by valve 20.

Forwardly of the platform 14 is disposed an auxiliary platform 21 upon which bottles may be laid as removed, say from cases. For operation in synchronism with the sterilizer, say as the cleansed bottles 8 are

discharged from the sterilizer, connection 22 from the automatic discharge extends to lever 23, as mounted by bracket 24, carried by the frame 13. This lever 23 has link 25, 60 therefrom for rocking lever 26, upstanding above the slotted platform 21, and in this rocking shoves bottles from this platform 21 on to the support 14 and by so doing forces the bottles out from under the brushes 15. 65 The lever 23 has extending therefrom link 27 to chute 28. Accordingly as the lever 23 is rocked to force a new series of dirty bottles on to the support 14, the set which was on this support which has been rotated and washed exteriorly is forced out and as directed by the chute 28, slide down as a series into a set of the pockets 6 on the endless conveyer 5. As these bottles move downward or away from the brushes 15, the longer 70 bristles of the brushes wash the bottoms, thereby effecting the washing of the entire bottle exteriors. Accordingly these bottles are clean on their outside as simultaneously delivered in series to this bottle interior 75 cleanser and sterilizer. The deliveries of the bottles in series to the sterilizer takes place automatically and there is no curtailment whatsoever in the capacity of the sterilizer.

What is claimed and it is desired to secure 80 by Letters Patent is:—

1. In a bottle cleansing machine having seats for receiving bottles, the combination of a bottle pushing delivery device for supplying bottles into said seats, bottle exterior 90 cleansing means, and a connection from the machine to operate said delivery device in synchronism therewith.

2. In a bottle cleansing machine having seats for receiving bottles, the combination of a bottle pushing delivery device for supplying bottles into said seats, and bottle washing means for cleansing the bottle exteriors while on the delivery device.

3. In a bottle cleansing machine having 100 seats for receiving bottles, the combination of a bottle pushing delivery device for supplying bottles into said seats, spray means and rotary brushes carried by said device for cleansing the exteriors of the bottles 105 while on said device.

4. In a bottle washing machine having bottle seats and an endless conveyor therefor, the combination of a delivery pushing device, connections for operating the device 110 in synchronism with the conveyor for delivering bottles from the device into the

seats of the machine to be shifted by said conveyor, and bottle cleansing means carried by the delivery pushing device.

5. For a bottle cleansing machine, the combination of a support for a series of bottles on said support, a plurality of rotary brushes for turning the bottles, spray means for delivering liquid to the brush rotated bottles as carried by said support, and a reciprocable member for pushing the bottles relatively to the brushes.

6. For a bottle cleansing machine, the combination of a support for a series of bottles, a plurality of rotary brushes for turning the bottles, spray means for delivering liquid to the brush rotated bottles as carried by said support and bottle pushing means for shifting the bottles from said support.

20 7. For a bottle cleansing machine, the combination of a support for a series of bottles, a chute from said support toward said machine, a plurality of rotary brushes

for turning the bottles on said support, spray means for delivering liquid to the brush rotated bottles as carried by said support and bottle pushing means operable independently of the rotation of said brushes for simultaneously shifting the series of bottles from said support and connected with said chute for raising and lowering said chute.

8. In a bottle cleansing machine, a bottle interior washer and sterilizer having bottle receiving pockets in series, the combination of a washer device embodying a support for bottles, a plurality of rotary brushes for turning the bottles on said support, spray means for delivering liquid to the brush rotated bottles as carried by said support, and pushing means for positively shifting the bottles serially into brush action receiving position, and from said support for delivery into said pockets.

In witness whereof I affix my signature.
ANDREW P. MURRAY.
